UNITED STATES PATENT OFFICE.

NATHAN BADGLEY, OF NEW YORK, N. Y.

IMPROVEMENT IN LEVER-JACKS.

Specification forming part of Letters Patent No. 38,936, dated June 23, 1863.

To all whom it may concern:

Be it known that I, NATHAN BADGLEY, of New York city, State of New York, have invented new and useful Improvements in Jacks for Hoisting Carriages and Wagons; and I do hereby declare the following to be a full and exact description thereof, reference being had to the accompanying drawing, and to the letters of reference marked thereon, making a part of this specification.

The nature of my invention consists in a reciprocating lever on the inside of jack and a curved slot with bearings in each of the sides.

A represents the view of jack with its main lever or handle, B, projecting from the bottom or platform C upward and outside behind the jack and between the side plates or frame, D. There is a curved slot, S, on each side of frame D, having one or more bearings, in which the axle E of the lever B operates, and is adjusted to the bearings to the height required. The side plates, D, are mortised permanently into the platform C, and are held together by pins or screw-bolts G.

H is the center plate or sliding head, with two or more square steps or rests, I, at top. It operates vertically and is self-adjusting. It has long vertical slots J, through which the bolts G pass, and are as upright guides for the plate H to secure its upward or downward

movement. This plate has a circular opening near its bottom, in which the circular head K of the short lever L is connected with the main lever or handle B by a wrist, M, and works on the handle fitting into it by a groove and mortise, so as to have a reciprocating motion and pass beyond its center, and supported by the shoulder or bearing P of the lever B to prevent its further movement. As the handle B is pressed downward, the lever L assumes a vertical position and raises the center plate, H, until steps I are brought in contact with an axle of carriage when it is raised, and the plate H keeps its position resting upon the lever L and curved end of handle B, and as the handle B is again raised the plate H falls down and adjusts itself again to its resting place.

What I claim as my invention, and desire to secure by Letters Patent, is—

1. The shape and construction of the reciprocating lever L, operating as herein described.
2. The curved slot with its bearings on each side of frame D.
3. The arrangement and combination of the devices of the plate H, lever L, with B, arranged and combined as herein described.

N. BADGLEY.
